Atty.

UNITED STATES PATENT OFFICE.

RICHARD G. HEBROCK, OF IRVINGTON, NEW JERSEY.

METALLIC RADIATOR THERMOMETER.

1,420,038.

Specification of Letters Patent. Patented June 20, 1922.

Application filed August 22, 1921. Serial No. 494,288.

To all whom it may concern:

Be it known that I, RICHARD G. HEBROCK, a citizen of the United States, residing at Irvington, in the county of Essex and State 5 of New Jersey, have invented certain new and useful Improvements in Metallic Radiator Thermometers, of which the following is a specification.

My invention relates to thermometers for 10 automobile radiators.

The object of the invention is to provide a simple and effective metallic thermometer adapted to be secured in the radiator cap and comprising a coiled spring of thermostatic 15 material secured at one end to the upper end of a hollow plug extending from the dial casing down through the casing nipple.

A further object of the invention is to provide a double pointer secured at its base to 20 the heat responsive device and working at opposite sides of a two face dial so that the position of the pointer will be clearly visible from the driver's position as well as at the front of the machine.

25 A further object of the invention is to provide a thermostatic spring of novel construction especially adapted for this type of thermometer.

I attain these objects by the mechanism 30 shown in the accompanying drawing in which—

Fig. 1 is a perspective view of my improved radiator thermometer from the rear.

Fig. 2 is a sectional front elevation 35 thereof.

Fig. 3 shows the spring, double pointer and the tubular attaching device removed.

Fig. 4 shows the blank from which the spring is formed.

40 Fig. 5 shows the blank from which double pointer is formed.

Fig. 6 is a central vertical transverse section on line 6—6 Fig. 2.

The circular casing 1 of the thermometer 45 has a central annular internal flange 2 and a depending hollow threaded attaching nipple 3 adapted to be secured to a radiator cap 28 by means of the nuts 26—27 which clamp the cap against a shoulder 4 formed on the 50 casing 1 at the upper end of the nipple 3.

The dial 5, preferably formed of two separate plates 6, is graduated from 0 to 300, on both of its faces.

Secured within the bore of the nipple 3 55 and extending at its upper end into the bottom of casing 1 is a spring-carrying tubular

support 7, which closely fits the upper reduced end of the bore of the nipple and has a transverse partition 8 near its upper end to prevent the entrance of water or steam 60 into the casing 1. The lower portion of the tubular support 7 is spaced away from the bore of the nipple so that the steam may have free access to the exterior of said support. This tubular support 7 is cut away at 65 its upper closed end to form a shoulder 9 to which is soldered or otherwise secured one end of a coiled thermostatic spring 10 formed of any of the usual materials used in this class of springs. The base or attaching end 70 11, of the spring 10 is provided with a slot 12 to afford two points of attachment to the shoulder 9 and to increase the strength of the spring. This slot 12 also permits the spring to have its coils passed through the 75 slot so that they will all lie in the same plane with the free end 13, projecting at the proper angle to receive the base of the double pointer 14, which pointer also lies in the same plane with the spring instead of to one 80 side thereof.

The spring 10 is formed from a flat blank as shown in Fig. 4.

The double pointer 14, is also formed from a single blank having two parallel fingers 15 85 connected at their inner ends by a base or cross piece 16 which cross piece forms the point of attachment to the spring.

The two members of the pointer 14 extend at opposite sides of the dial 5 and the dial is cut away at its lower edges as at 16 to accommodate the spring 10 and allow of the 90 free working. The double pointer 14 is rendered luminous in any approved manner so that the same may be readily observed at 95 night.

The casing 1, is closed by means of glass discs 17, 17, held in place by the outer rings 18—18, and the screws 19, suitable washers 20 being placed at the inner sides of the 100 rings. The screws 19 after passing through the rings 18 and the washers 20 enter threaded apertures on the annular flange 2.

The operation will be readily understood by those familiar with coil spring thermostatic thermometers in which the unequal expansion of the metal causes the spring to bend and so move the pointer along the dial. 105

What I claim is—

1. A metallic radiator thermometer comprising a casing provided with a tubular depending attaching nipple, and having a two 110

- 2 faced graduated dial, a thermostatic spring secured at one end in the casing and provided at its free end with a double pointer secured at the base to the free end of the spring with its two members respectively extending over opposite faces of the dial.
3. A metallic radiator thermometer comprising a casing provided with a tubular depending attaching nipple, and having a two faced graduated dial, a support closing communication between the casing and its attaching nipple, a thermostatic spring secured at one end to the upper end of said support and a double pointer connected at its base to the free end of the spring with its two arms respectively extending at opposite sides of the dial.
4. In a metallic thermometer, a coiled thermostatic spring having a slotted attaching end; the coils of the spring extending through said slot and lying in the same plane and a pointer projecting from the free end of the spring.
5. In a metallic thermometer, a two faced dial, a coiled thermostatic spring having a slotted attaching end; the coils of the spring extending through said slot and lying in the same plane and a double pointer projecting from the free end of the spring in the plane
6. A metallic radiator thermometer comprising a casing having a double face dial enclosed between its front and rear glazed faces, the lower edge of the dial having an opening therethrough, a tubular attaching nipple depending from the lower edge of the casing, a spring supporting means closing the upper end of the attaching nipple, a coiled thermostatic spring secured at one end to said supporting means within the dial opening and a double pointer secured to the free end of the spring with the two members respectively extending along opposite faces of the dial.
7. A thermostatic thermometer comprising a casing provided with a central depending tubular attaching nipple, a dial within the casing, a tubular support closing the upper end of the tubular attaching nipple and extending down into said nipple in spaced relation therewith, a coiled thermostatic spring secured at one end to the upper closed end of the support and a pointer extending from the outer free end of the said spring.
8. A thermostatic thermometer comprising a casing glazed on both sides and having an intermediate two faced dial and a central depending tubular attaching nipple, having closing means at its upper end, a thermostatic spring secured at one end in the casing at the upper closed end of the nipple and a double pointer secured to the upper free end of the spring in the plane thereof with its two members extending along the opposite faces of the dial.

In testimony whereof I affix my signature.
RICHARD G. HEBROCK.
